UNITED STATES PATENT OFFICE

133,214

DESIGN FOR AN ELECTRIC LIGHTING FIXTURE

Albert J. D. Ohm, Buffalo, N. Y., assignor to
Markel Electric Products, Inc., Buffalo, N. Y., a
corporation of New York

Application July 15, 1941, Serial No. 102,156

Term of patent 7 years

To all whom it may concern:

Be it known that I, Albert J. D. Ohm, a citizen of the United States, residing at Buffalo, in the county of Erie and State of New York, have invented a new, original, and ornamental Design for Electric Lighting Fixture, of which the following is a specification, reference being had to the accompanying drawing, forming a part thereof.

In said drawing:

Figure 1 is a perspective view of an electric lighting fixture embodying my new design.

Figure 2 is a bottom plan view thereof.

Figure 3 is an end elevational view.

Figure 4 is an enlarged fragmentary section through the shade and is taken along line 4—4 of Figure 2.

The characterizing features of my design for the electric lighting fixture shown, reside in the portions shown in full lines and more particularly in the specific ornamental figures on the cap pieces at the ends of the light diffuser element as best shown in Fig. 3 of the drawing.

I claim:

The ornamental design for an electric lighting fixture, substantially as shown and described.

ALBERT J. D. OHM.
